UNITED STATES PATENT OFFICE

ALBERT FRECH, OF ST. LOUIS, MISSOURI, ASSIGNOR TO EISENSTADT MANUFACTURING COMPANY, OF ST. LOUIS, MISSOURI, A CORPORATION OF MISSOURI

DESIGN FOR A COLLAR HOLDER

Application filed January 31, 1930. Serial No. 34,355. Term of patent 14 years.

To all whom it may concern:

Be it known that I, ALBERT FRECH, a citizen of the United States of America, residing at the city of St. Louis, State of Missouri, have invented a new, original, and ornamental Design for a Collar Holder, of which the following is a specification, reference being had to the accompanying drawing, forming a part thereof.

In the drawings, Figure 1 is a side view, and Figure 2 is a top view of a collar holder embodying my new design.

I claim:

The ornamental design for a collar holder as shown.

ALBERT FRECH.
